UNITED STATES PATENT OFFICE.

GEORGE T. JOHNSON AND GEORGE M. MURPHY, OF COLUMBUS, OHIO, ASSIGNEES TO THE BUCKEYE STEEL CASTINGS COMPANY, OF COLUMBUS, OHIO.

CAR-COUPING.

1,128,987.

Specification of Letters Patent. Patented Feb. 16, 1915.

Application filed January 26, 1914. Serial No. 814,507.

To all whom it may concern:

Be it known that we, GEORGE T. JOHNSON and GEORGE M. MURPHY, of Columbus, in the county of Franklin and State of Ohio, have invented certain new and useful Improvements in Car-Couplings; and we do hereby declare the following to be a full, clear, and exact description of the invention, such as will enable others skilled in the art 10 to which it appertains to make and use the same.

Our invention relates to an improvement in car couplings, and particularly to means for lifting the locking block to uncouple or 15 release the knuckle, and it consists in the details of construction as will be more fully described and pointed out in the claims.

In the accompanying drawings, Figure 1 is a view in front elevation of a car coupling 20 embodying our invention, and Figs. 2 to 6 inclusive are views of modified forms.

1 represents a coupling head, and 2 the knuckle which latter is locked in closed position by a vertical sliding pin or locking 25 block in the well known manner. The lower end of the pin or block is accessible through an opening in the bottom of the head, so that it may be engaged by the free end of the finger 3 of the bell crank lever 4. This lever 30 is pivoted at 5 to the bracket 6, shown in dotted lines in Fig. 1, which bracket is cast integral with the head 1, and the lever is normally sustained with its finger 3 out of contact with unlocking mechanism but actu- 35 ally extending through the opening in the floor of the head, and under the locking pin or block by the extension 4^a of the lever bearing against the head of the coupling as will be hereinafter more fully explained, and 40 it is actuated by the pitman 7, pivotally connected at 8 to the depending integral extension 9 on lever 4, the extension having a hole through same for the attachment of the pitman 7.

45 The pitman 7 extends upwardly and has a universal connection with the arm 10 of the rock shaft 11 the latter being pivotally secured to the end sill, or front of the car, and is provided at each end with an arm 12 by 50 which the shaft 11 may be rocked.

Lever 4 is provided with an upward extension 4^a, from its hub, which latter projects up along the side of the head and is pro- 55 vided at its upper end with an inwardly projecting toe 4^b which engages the side of

the coupling head and limits the drop of the lever, so that its weight, and the weight of the pitman will hold its toe 4^b against the head and prevent any downward swinging movement of the lever. When in this position the finger 3 of lever 4 is just below and out of contact with the locking pin and block, but is maintained within the recess in center of head provided for it, thus using the bottom of draw head as a guide for 65 finger 3.

In the construction shown in Figs. 2, 3 and 4 the upward extension 4^a of the lever is enlarged laterally so as to bear on the top of the bracket 6, instead of against the side 70 of the coupling.

In the construction shown in Fig. 5, the upward extension of the levers bear against the rear wall 6^a of the bracket 6, while in the construction shown in Fig. 6, the upward 75 extension has an inwardly projecting toe 4^d which rests against the outwardly projecting shelf 15, which may be integral with the coupling head, but which is preferably also integral with the bracket 6. 80

Normally the lever 4 stands in the position shown in Fig. 1, and when in such position, its finger 3 is down and is not lifting the pin or locking block. By pulling up on the pitman, the finger 3 moves upward in the 85 coupling head and engaging the locking pin or lock lifting means, lifts the same a distance sufficient to release the knuckle. When the lever is released it drops to the position shown in Fig. 1, but as the upward extension thereon engages an abutment before the lever reaches its center of gravity the latter will be held in proper position. 90

Having fully described our invention what we claim as new and desire to secure 95 by Letters-Patent, is:—

1. The combination with a coupling head, a bracket projecting from the same, a lever pivoted adjacent its upper end to said bracket and lifting means connected with 100 said lever adjacent the free end of the latter, the said lever being also provided adjacent its free end with a finger adapted to pass through the floor of the coupling for raising the knuckle locking means, and at its 105 other or pivoted end with a shoulder to engage the bracket for limiting the drop of the lever.

2. The combination of a coupling head, a bracket projecting from same, a lever pivot- 110

ed adjacent its upper end to said bracket and provided at its opposite end with a finger adapted to pass through the floor of the coupling for raising the knuckle locking means, the said lever being provided at its upper end with a shoulder adapted to overhang the bracket and limit the drop of the lever, and means for actuating the said lever.

Copies of this patent may be obtained for five cents each, by addressing the "Commissioner of Patents, Washington, D. C."

In testimony whereof, we have signed this specification in the presence of two subscribing witnesses.

GEORGE T. JOHNSON.
GEORGE M. MURPHY.
